UNITED STATES PATENT OFFICE.

OSCAR J. SUNDSTRAND, OF ROCKFORD, ILLINOIS, ASSIGNOR OF ONE-HALF TO HENRY LEE SMITH, OF CHICAGO, ILLINOIS, AND ONE-HALF TO EDWARD G. PETERSON, OF ROCKFORD, ILLINOIS.

PNEUMATIC LIFTING JACK.

Application filed December 24, 1921. Serial No. 524,803.

To all whom it may concern:

Be it known that I, OSCAR J. SUNDSTRAND, a citizen of the United States, residing at Rockford, in the county of Winnebago and 5 State of Illinois, have invented certain new and useful Improvements in Pneumatic Lifting Jacks, of which the following is a specification.

This invention relates to lifting jacks of 10 the portable floor-jack type primarily adapted for use in connection with motor vehicles for purposes well known in this art.

The chief object is to provide a generally improved lifting jack actuated by fluid pressure, such as compressed air, for raising a vehicle at any desired point. I have aimed to construct the lifting jack in such novel manner that it will save time, labor and effort by reason of the fact that it may be 20 quickly and conveniently placed in position and instantly operated simply by opening an air supply valve to raise the vehicle and an exhaust valve to lower it. This device is especially adapted for use in garages where it 25 is frequently in demand. It may also be carried on automobiles and trucks for use on the road, this being particularly desirable when the vehicle equipment includes a motor driven air pump or carries compressed air 30 for other purposes.

In furtherance of the foregoing, my invention contemplates among other things, the following objects, namely,—the provision of a portable fluid-actuated jack including a pressure supply pipe extending substantially radially from the cylinder and equipped at its outer end with a handle, whereby to enable quick placement and removal of the jack without reaching under 35 the vehicle; to provide a novel handle including a check valve at the air supply end and a quick-acting exhaust valve; to provide a shoe on the base end of the cylinder for preventing it from rolling when it is turned 40 on one side with its handle uppermost, which also prevents loss of oil or lubricant from the cylinder through the vent opening located at this uppermost side; to provide an expandable packing for the piston and novel 45 means for adjusting or expanding this packing from the exterior of the cylinder to insure against the loss of air in the operated position; and to provide a jack rod associated 50 with the fluid-actuated element in a novel

manner, permitting adjustment of such rod 55 for lifting to different elevations.

Still another object is to provide a fluid-actuated jack constructed in such simple and novel manner that it will be thoroughly practical and durable for the purposes intended 60 and may be commercially produced at a comparatively low cost.

Other objects and attendant advantages will be appreciated by those familiar with this art as the invention becomes better understood by reference to the following description when considered in connection with the accompanying drawings:

Fig. 1 is a side elevation of a portable fluid-actuated jack embodying my invention, 70 showing the jack in operative position;

Fig. 2, a top view of the jack partly in section;

Fig. 3, a vertical section through the jack taken on the line 3—3 of Fig. 2;

Fig. 4, a fragmentary view showing the jack rod partially extended from the piston rod;

Fig. 5, a section similar to Fig. 4, showing the piston partially elevated by fluid pressure;

Fig. 6, a fragmentary section showing the piston elevated as in Fig. 5 and the jack rod adjusted as shown in Fig. 4;

Fig. 7, a longitudinal section through the 85 jack showing the piston in the elevated position, the jack rod removed and a wrench applied for adjusting the piston rod to expand the packing;

Fig. 8, a cross section taken on the line 90 8—8 of Fig. 7; and

Fig. 9, a side elevation showing the jack turned on its side in an inoperative position.

The cylinder body 11 is preferably of cast iron, giving it ample weight, strength and 95 durability for the purposes intended. Said body in its preferred form has a closed base end 12 and a removable top end or head 13 at present threadingly engaged on the cylinder. The piston may be of any suitable construction including provision for an expandable packing, and at present consists of centrally apertured plates 14 and 15 between which is interposed an expandable packing disk 16, which at present is of an 100 oil-proof rubber composition. These plates and the packing are clamped between the inner end of the piston rod 17 and a nut 18

threadingly engaged on a reduced extension or bolt end 19 of the piston rod, which bolt end passes through the apertures in the plates 14 and 15. Suitable means, such as 5 a pin 21 fixed on the plate 15, prevents rotation of the nut 18 with respect to the plate 15. The foregoing construction enables expansion of the packing by adjustment from the exterior of the cylinder. That 10 is, assuming the piston held by fluid pressure in the elevated position shown in Fig. 7, the operator may apply a wrench 22 to the milled upper end 23 of the piston rod 17 and turn such rod to tighten the nut 18. This 15 increased compression of the packing will expand it to effect the desired air-tight seal between the piston and cylinder wall. It will be manifest that by means of such an adjustment the packing may, when worn, be 20 easily expanded to maintain the proper air seal.

In order to increase the range of use of the jack I have provided an extensible jack rod. The jack rod 24 at present in the form 25 of a screw, is loosely slidable in the hollow piston 17 and equipped at its upper end with a seat 25 and a nut 26 fitting the screw. The jack rod drops to a lowermost position in the piston rod limited by the nut 26. By adjusting this nut on the screw, the latter may 30 be raised or lowered as the case may be, to thereby increase or diminish the height to which the seat 25 will be elevated, it being noted that in each instance the length of the 35 piston stroke or lift is the same.

Coming now to the admission of fluid pressure to the cylinder for actuating the piston, it will be noted that my invention 40 contemplates the provision of a combined handle and pressure-supply pipe, thereby providing an exceptionally simple, practical and desirable construction. The supply pipe 27 is threadingly engaged at its inner end in a boss 28 formed integral with and medi- 45 ally between the ends of the cylinder body as shown in Fig. 1, and radially with respect thereto as shown in Fig. 2. The pipe 27 connects with a passage 29 in the cylinder body communicating with a fluid induction and 50 eduction port 31 at the base end thereof. The pipe 27 carries at its outer end a handle 32 in the form of a T-pipe connection, one arm 33 of which is threadingly engaged on the pipe 27. The remaining arms 34 and 35 55 carry suitable pressure check and exhaust valves. The check valve 36 may be of any suitable type having a threaded nipple for attachment of hose connections. I have chamfered or beveled the end 37 of the arm 60 34 providing a reduced outer end to permit insertion of the valve 36 into the nozzle of an air-supply hose. The exhaust valve in the opposite arm 35 may be of any construction, but preferably such as will allow quick 65 exhaust. For this purpose, I have provided

a threaded shut-off member 38 in the exhaust passage 39, said member carrying a rubber seat 41 and having a knurled outer end and slotted threaded end 42, whereby the exhaust passage may be quickly closed or opened by 70 rotation of the member 38, as will be observed.

From the foregoing, it will be manifest that by reason of the handle construction which serves likewise as the fluid pressure 75 supply pipe, the operator may not only very conveniently position the jack beneath a vehicle but having done so, the supply and exhaust ends for the fluid pressure are immediately at hand and ready for use as they 80 form part of the means for locating the jack in position. Furthermore, by utilizing a relatively long rigid supply pipe as a handle and arranging it to extend radially from the cylinder the handle may be very conveniently 85 manipulated from its outer end to position the cylinder beneath a vehicle. The cylinder and handle organization is also particularly desirable in that the handling and moving of the jack from place to place is expedited. 90 That is, when withdrawing the jack from beneath a vehicle the operator simply grasps the outer end of the handle, and pulls upwardly and outwardly, thereby withdrawing the jack from under the vehicle, and inasmuch as the heavy cylinder is thus suspended from the handle it may be very conveniently carried about. When not in use, the cylinder will be positioned on the floor as 95 shown in Fig. 9, with the handle uppermost. 100 In this position, the cylinder is prevented from rolling sidewise by a shoe 43 on the base end of the cylinder diametrically opposite from the handle 27. This shoe also acts as a fulcrum when swinging the cylinder body into and out of upright position and is beveled as shown to facilitate this movement and also the sliding of the body into and out of position beneath the vehicle.

In the use of this jack I prefer to add a 110 small quantity of oil to the cylinder above the piston as indicated in the drawings, to promote smooth action of the piston and insure a better air seal. A small vent opening 44 is provided to allow escape of air from 115 above the piston when pressure is applied therebeneath. This opening is positioned above the oil level when the piston is elevated and is located at the handle side of the cylinder to prevent loss of oil when the cylinder is turned on one side when not in use. The matter of placing the jack in operative position and removing it has been described, and in this regard, attention is directed to the combination of the handle 120 and the air supply and exhaust connections which enables the jack lifting operation to be immediately performed after location of the jack, and on the other hand, immediate removal of the jack after release of the air. 125 130

It will also be noted that practically no effort on the part of the operator is required in operating this jack, other than to simply push the jack body into position beneath the vehicle and to pull it out after use. Adjustment of the nut 26 to change the elevation of the seat 25 may obviously be made very quickly and easily. Lengthwise adjustment of the packing to effect a positive seal may be effected without disassembling the jack or removing any parts. The jack comprises but comparatively few parts, constructed in such simple manner as to be capable of production at a comparatively low cost and to serve very effectually the purposes intended. By utilizing a cylinder as the jack-supporting body and base, a very stable support is obtained.

It is believed that the foregoing conveys a clear understanding of the objects prefaced above, and while I have illustrated but a single working embodiment it should be understood that changes might be made in the construction and arrangement without departing from the spirit and scope of the invention as expressed in the appended claims.

I claim:

1. A portable jack of the character described, comprising a cylindrical body one end of which forms a base on which the body rests in the operative position, a piston in the cylinder having a jack extending from the opposite end thereof, the piston being adapted to be raised by fluid pressure in the cylinder and lowered by exhaust of said pressure, a fluid-pressure supply pipe connected to the body and disposed in a plane at substantially right angles to the longitudi-

nal axis of said body, a handle on the outer end of said supply pipe, and means on the body for holding it from rolling when positioned on one side with its handle upright.

2. A portable jack of the character described, comprising a cylinder having a base and a head at opposite ends and adapted to rest on its base when in the operative position, a piston jack in the cylinder passing through the head and adapted to be raised by fluid pressure and lowered by exhaust thereof, a fluid pressure supply pipe attached to the cylinder and extending radially therefrom and equipped at its outer end with a handle, and a shoe on the base end of the cylinder diametrically opposite from said pipe, providing a fulcrum on which the cylinder is adapted to be swung by said handle from said upright operative position to a lowered horizontally disposed position with the handle upright, in which latter position the cylinder is prevented from rolling sidewise by said shoe.

3. A portable jack of the character described comprising a cylinder having a base and a head at opposite ends and adapted to rest on its base when in the operative position, a piston jack in the cylinder passing through the head and adapted to be raised by fluid pressure and lowered by exhaust thereof, an elongated handle radiating from one side of the cylinder and adapted to be manipulated for positioning the cylinder on its base and for tilting the cylinder to a horizontal position, and a shoe on the cylinder for preventing it from rolling sidewise when in said horizontal position with its handle uppermost.

OSCAR J. SUNDSTRAND.
